UNITED STATES PATENT OFFICE.

CLAUDIUS V. BOUGHTON, OF BUFFALO, NEW YORK.

BICYCLE-LAMP.

SPECIFICATION forming part of Letters Patent No. 594,516, dated November 30, 1897.

Application filed February 25, 1896. Serial No. 580,701. (No model.)

To all whom it may concern:

Be it known that I, CLAUDIUS V. BOUGHTON, a citizen of the United States, residing at Buffalo, in the county of Erie and State of New York, have invented certain new and useful Improvements in Bicycle-Lamps; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

My invention relates to improvements in lamps which are specially adapted for use upon bicycles.

The object of my invention is to provide an improved lamp which is particularly constructed for carrying an improved taper which forms the subject-matter of an application filed by me on the 25th day of November, 1895.

To that end my invention consists of certain details of construction, all of which will be fully hereinafter described, and pointed out in the claim.

In the drawings, Figure 1 is a side elevation, and Fig. 2 is a front elevation, of my improved lamp complete. Fig. 3 is a rear elevation of the same with the back portion of the reflector removed. Fig. 4 is a central vertical section. Fig. 5 is a top plan view. Fig. 6 is an under side view with the taper-holder removed. Fig. 7 is a detached detail view of the under side of the cap and depending deflector. Fig. 8 is a side elevation of a special form of spring-socket for carrying the lamp. Fig. 9 is a central vertical transverse section of the spring-socket. Fig. 10 is a top plan view of the spring-socket, and Fig. 11 is a vertical section taken on the line $\alpha\alpha$ of Fig. 10.

Referring to the drawings, it will be seen that the hollow casing or shell has the configuration of two intersecting cylinders, of which 1 is the vertical and 2 is the horizontal. Upon one side of the horizontal cylinder 2 is an elongated opening 3, covered by a stationary frame 4, in which is set a piece of red glass 5. On the opposite side is a similar opening 6, and 7 is a loose frame also carrying red glass 8 and adapted for vertical ad-

justment in the ways 9 to cover the opening 6, as shown in Fig. 1, or to be slid vertically away from the same to permit of the insertion of a match to light the lamp. At the lower end of cylinder 1 is the removable taper-holder 10 with bayonet-joint 11 for holding it in place.

12 12 are the arms of a bracket, their inner ends being riveted to the cylinder 2 along its intersection with cylinder 1 and their outer ends carrying a vertical socket 13 with clamping-screw 14 for securing it to the frame of the bicycle. Just under the arms 12 12 and 15 in the cylinder 1 are the draft-holes 15. The lower wall of the cylinder 2 within its intersection with the cylinder 1 is provided with the central opening 17, through which the flame ascends. Surrounding this opening 17 are the draft-holes 18.

The upper end of the cylinder 1 is provided with the annular enlargement 19, in the under wall 20 of which are the series of draft-holes 21. Upon the side wall of this 75 enlargement 19 are a similar series of draft-holes 22. A cylindrical deflecting-wall 23 rises above the level of the draft-holes 21, as clearly shown in Fig. 4.

24 is a flanged removable cap fitting down 80 snugly upon the enlargement 19, and 25 is a deflector formed of a convex disk and depending from a rod 26, centrally secured to the cap 24. This deflector extends down below the level of the line of draft-holes 21 in 85 the under wall 20 of the enlargement 19.

The front end of cylinder 2 has an annular enlargement 27, within which is secured the conical reflector 28, its inner smaller end being cut away at top and bottom, as at 29 29, 90 for the upward passage of the flame. The rear end of the cylinder 2 is provided with the flanged removable concave reflector 30. A glass 31 is secured across the conical reflector 28. Upon the upper and lower side of the inner wall 32 of the annular enlargement 27 are the draft-holes 33, and just under and over these holes 33 and in the conical reflector 28 are similar draft-holes 34. These draft-holes 33 and 34 permit a passage of air across the inner face of the glass 31, which prevents an accumulation of moisture thereon.

The special form of spring-socket shown in Figs. 8, 9, 10, and 11 is constructed as follows:

36 36 are arms similar to the arms 12 12 (shown in Figs. 1, 4, 5, and 6) and are secured to the sides of the lamp in the same manner and at the same points as the arms 12 12. The outer 5 ends of the arms 36 36 are pivoted to the end walls of the socket 37, as at 38. The rear face of the socket has the outwardly-extending recess 39, adapted for the loose reception of the nut 40, with which the thumb-bolt 41 is in 10 screw-threaded engagement and by means of which the lamp is secured to the frame of the bicycle. 42 is a leaf-spring with its ends curved in opposite directions, its outer end 43 being rigidly secured to the rear face of the socket 15 37 and its inner end 44 being loosely bent around the cross-bar 45, which extends across between the two arms 36 36. With this improved construction the jarring of the bicycle in passing over inequalities in the road is 20 neutralized in a most effective manner without affecting the steadiness of the lamp, thereby precluding the possibility of extinguishing the lamp by any sudden and violent jolt communicated from the machine through the arms 25 36 36.

A taper or lamp is placed in the holder 10, which is then adjusted in position, as shown in Fig. 1. The taper or lamp can be lighted before being placed in position or afterward 30 with a lighted match inserted through the opening 6, the frame 7 having been pushed up for that purpose. The draft of air for supporting combustion enters through holes 15 and passes up and around the flame through 35 holes 18.

The exits for the draft are through holes 19

21 and the circular series of holes 35 in the cap 24. The cylindrical wall 23 serves to deflect the air entering through holes 21 and conduct it upwardly for egress through holes 22 and 35. 40

Should air be forced in through holes 21 or 22, as might happen while riding at great speed or against a high wind, the depending convex disk 25 will deflect it equally to the sides of the cylinder 1 and thereby prevent 45 any concentration of the same against the flame of the taper or lamp. The arrangement of the conical reflector 28 and rear concave reflector 30, as shown, practically produces a parabolic reflector, and the concave reflector 50 being removable permits of its reflecting-surface being readily cleaned and polished when necessary without disturbing the light.

I claim—

In a bicycle-lamp, the combination with the 55 socket 37 for securing the lamp to the frame of the bicycle, of the arms 36, 36, rigidly secured to the body of the lamp at their forward ends and pivoted to the socket 37 at their rear ends and the spring 42 with its ends curved 60 in opposite directions its outer end 43 being rigidly secured to the rear face of the socket 37 and its inner end being loosely bent around the cross-bar 45 which extends across between the two arms 36, 36. 65

In testimony whereof I have signed my name to this specification in the presence of two subscribing witnesses.

CLAUDIUS V. BOUGHTON.
